UNITED STATES PATENT OFFICE.

NIELS A. CHRISTENSEN, OF MILWAUKEE, WISCONSIN.

CONTROL VALVE MECHANISM.

Continuation of application Serial No. 453,798, filed March 19, 1921, Patent No. 1,517,533, dated December 2, 1924. This application filed May 24, 1924. Serial No. 715,753.

The invention relates to valve mechanism. The object of the invention is to provide a valve mechanism for starting systems for internal combustion engines of the type shown in my prior United States Letters Patent No. 1,185,874, of June 16, 1916, and No. 1,253,669, of January 15, 1918, and in my United States Letters Patent No. 1,517,533, of December 2, 1924; of which this application as to the starter valve mechanism shown therein is a continuation.

A further object of the invention is to provide a starter valve mechanism that may be operated by the foot of the driver, and with provision for venting the carburetor chamber so that the pressure therein may be reduced after a starting operation to permit the float chamber filling up for a subsequent starting operation.

20 The invention further consists in the several features hereinafter set forth and more particularly defined by claims at the conclusion hereof.

In the drawings: Fig. 1 is a general view 25 in side elevation of starting apparatus embodying the invention as applied to a typical four-cylinder engine, in connection with a magneto, parts being shown in section;

Fig. 2 is an enlarged vertical sectional view 30 of the driver's or controlling valve mechanism embodying the invention;

Fig. 3 is a partial vertical cross-sectional view on the line 3—3 of Fig. 1, the distributing valve and valve case being removed.

35 Referring to Fig. 1, the apparatus comprises a compressor 4, a distributing valve mechanism, a carburetor 5, a compressor governor or controller 6, and a through drive shaft 7 assembled for mounting as a unit in 40 the place of the usual magneto 8 and driven from the same shaft, as for example, the pump shaft 9 of the engine, with which the drive shaft is connected at one end, the magneto being connected with the other end 45 of said drive shaft, and mounted with the starter unit on the same bracket or base plate 10, which may be adapted for attachment to engine bases or frames of different makes or kinds.

50 In addition to said unit, the apparatus comprises a compressed air reservoir 11, a driver's valve 12 controlling the connections between the reservoir, compressor, distributing valve and compressor governor.

55 The distributing valve is not shown in detail

herein, as it is fully shown and described in my United States Letters Patent No. 1,517,533, hereinbefore referred to, and includes a rotary disk valve member 13' driven from the shaft associated with the drive of the compressor and cooperating with a seat member 13 secured with a cover 14 to the main case section 15, Fig. 3. The seat member 13 is formed with a central bore in axial alignment with the shaft 16 associated with the 60 compressor and distributor valve and with ports 17' which cooperate with ports 17 in the distributor valve 13' and register with passages 17" in the case section 15, which are each connected by piping 18 with one of the engine cylinders through a check-valve 19, like or similar to those described in Letters Patent No. 1,185,784. The distributor valve 13' controls the passage of compressed air mixed with fuel from a passage 20 in 65 the member 15 aligned with a passage 21 in the case section 15 to the ports 17, Fig. 1. The distributor valve 13' is preferably mounted on a short shaft 16' driven by the shaft 16 but having a slight longitudinal 70 movement to relieve the valve 13' of wear. The drive shaft 16 is driven from the shaft 9 by gear 23 on the shaft 7 meshing with a gear 24 on the shaft 16 and this shaft 16 drives the compressor when permitted to do 75 so by the governor mechanism, more particularly shown and described in the aforementioned application Serial No. 453,798.

The carburetor includes a fuel chamber 25, 80 here shown as formed in the main case section 15, though it may be separate therefrom, said chamber being supplied with fuel from a float chamber 26 through a pipe 27.

The passage 21 is connected to the driver's valve by a pipe 28 and a two-way fitting 29 which is also connected by a pipe 30 to the compressor governor mechanism. The passage 21 communicates adacent its outer end with the upper part of the chamber 25 through a passage 31, as shown in Fig. 3, the 95 passage 21 being slightly restricted as compared with the bore for the fitting 29 so that the liquid fuel in the carburetor chamber will be subjected to a slightly higher pressure 100 than prevails in the passage 21 when compressed air is admitted thereto.

A spray nozzle 32 extends upwardly from the lower part of the chamber 25 into the passage 21 for carburetting the compressed air as it passes to the distributing valve. 110

The nozzle is inserted in place and may be reached for inspection and for removing any obstruction therefrom, through an opening in the case section 15 into the passage 21 opposite the nozzle, which opening is normally closed by a cap-screw 33.

The connection between the float chamber 26 and the pipe 27 is provided with a check-valve 34, closing toward the float and having its stem guided in a cage 35, which is removably threaded in the bottom of the float chamber and formed at the lower end with a valve seat, the valve being held in place and its movement limited by a nut or collar fixed on the upper end of the valve stem and slotted on its lower side to allow fuel to pass from said chamber 26 around the stem and to the pipe 27.

The top or upper part of the float chamber is connected by a pipe 36 with a fuel supply tank 37 and this pipe is provided, as shown in Fig. 1, with a shut-off cock 38.

As shown, the pipe 36 connects with a removable cover 39 of the float chamber in which is threaded a removable valve cage and seat 40 provided with a cut-off valve 41 having a stem projecting downwardly into the upper part of the float chamber and engageable with the float 42. The valve is held in place in the cage when the cover is removed and its movement is limited by a screw 43 threaded in the lower part of the cage with its head in position to engage with a collar on the valve stem.

The end of the pipe 36 is shown provided with a strainer 44 and the upper reduced end of the cage 40 in which the valve is seated is provided with a cap 45 with small grooves formed in the cage adjacent thereto to prevent impurities that may be carried with the fuel from reaching the valve and interfering with its operation. Impurities deposited in the annular space below the cap 45 may be removed from time to time by removing the cover 39 and taking out the cage 40.

The cover 39 is provided with a vent opening 46 to the atmosphere, and overflow therefrom indicates trouble with the valve 41.

With the construction of carburetor herein described, it will be noted that when compressed air is introduced into the mixing passage 21 and pressure is put upon the fuel in the carburetor chamber 25, that the check-valve 34 will close and thus shut off the float chamber during a starting operation. When the compressed air is not flowing through the passage 21 provision has been made for reducing the pressure in the fuel chamber 25 to atmosphere so that the float chamber and its parts will function normally to supply said fuel chamber with fuel.

The driver's or controlling valve 12, as

shown in Figs. 1 and 2, comprises a casing 50 formed with a flange 51 for fastening it to the foot-board of a truck or car and provided with ports 52, 53 and 55 to which the pipes 56, 57 and 28 are connected. The pipe 56 connects said valve structure with the reservoir 11 and the pipe 57 connects the discharge side of the compressor 4 with said valve casing.

The valve case is also formed with a valve chamber 58 and inwardly directed seats at opposite ends thereof, and is provided with valves 59 and 60, guided therein by recessed heads or enlargements 61 of their stems, and adapted to close in opposite directions against the seats, to which they are normally held by a spring 62 interposed between the headed parts of their stems. The valve 59 controls passage of air from the compressor through pipe 57, chamber 58, port 52 to the pipe 56 and the valve 60 controls the passage of compressed air from the reservoir through pipe 56, port 52, chamber 58 to a passage 63 and port 55 which connects with the pipe 28 conducting compressed air to the carburetor and to the pipe supplying compressed air to the governor.

A push-pin 64, guided in a nut 65 removably threaded in the upper end of the valve case, is adapted to open the valve 60. The push-pin is flattened or formed with an air vent passage 66 on one side, and the upper end of the pin is formed or provided with a relief valve 67, fitted to seat on a seat 68 on the upper end of the nut to shut off passage of air through said vent when closed.

A push-button 69 for operating the push-pin 64 to open the valve 60 and close the valve 67 is guided in a cap 70, which is removably threaded on the upper end of the case 50 above the flange 51. The cap is provided with a vent opening 71.

The lower part of the valve case containing the valve 59 is made in a separate section, which is threaded into or otherwise detachably fastened to the body of the case for convenience in construction and assembly of parts of the device.

In the operation of the apparatus, the reservoir 11 being charged with compressed air at a pressure, say of 225 pounds per square inch, to start the engine the operator presses the push-button 69 down with his foot. The push-pin 64 being thus thrust downward opens the valve 60 and closes the valve 67. Compressed air is thus admitted from the reservoir through the pipe 56 into the passage 21 from which it passes to the distributor mechanism, more particularly shown in said United States Letters Patent No. 1,517,538; by which it is introduced into the engine cylinders mixed with the liquid fuel it has taken from the chamber 25 while passing the nozzle 32 in said pas-

sage, the fuel thus introduced being ignited by the ordinary electric ignition apparatus of the engine. When the air passes to the passage 21 some of it passes to the pipe 30 and acts on the governor mechanism, more particularly shown and described in said Patent No. 1,517,533, which then establishes a drive between the engine and the compressor, and air is delivered by the compressor 10 through pipe 57 past valve 59 to the reservoir for subsequent starting operations or for use in the operation of the air brakes associated with the vehicle.

If it is desired at any time, in case compressed air is required for other purposes than starting, for instance, for the operation of air brakes, the compressor can be started when the engine is running to replenish the reservoir, by simply depressing 20 the push-button 69 of the driver's valve.

The carburetor chamber 25 is kept supplied with fuel automatically through the float chamber 26, in which a substantially constant level is maintained by the float 42 25 closing the valve 41 when the fuel rises in the float chamber above a certain lever, and permitting the valve to open by gravity when the fuel descends below that level.

When the distributing mechanism of the apparatus is not operating and the fuel in the carburetor chamber is not subjected to pressure, the level of the fuel therein will be the same as that in the float chamber 26 and remain at that level, but when pressure 35 is admitted to the carburetor chamber it will be transmitted through the oil therein and through the connection between it and the float chamber and will close the check-valve 34 which will remain closed, resulting 40 in the lowering of the fuel level in the carburetor chamber by reason of fuel being drawn therefrom by the operation of the starter, until the pressure is released from the carburetor chamber 25, which occurs 45 when the operator lets the push-button 69 return to its upper position, permitting valve 67 to open and valve 60 to close, and the air under pressure in the chamber 25 and passage 21 flows back through pipe 28 50 to passage 63 through vents 66 and 71 to atmosphere, whereupon the fuel will rise in the chamber 25 to the level of that in the float chamber. The descent of the fuel level in the float chamber, causing the float to descend, releases the valve 41 thereby admitting fuel from the supply pipe 36 until the 55 normal level therein and in the carburetor chamber 25 is restored.

The automatic check-valve 34 in the connection between the carburetor chamber 25 and the float chamber 26, by closing whenever compressed air is admitted to the carburetor chamber, prevents the float from being subjected to, and collapsed or affected by, the

pressure required for the operation of the starting apparatus and the admission of air to the fuel supply line.

From the foregoing description it will be noted that the starter valve mechanism herein described establishes communication between the starter unit and the reservoir, between the compressor and the reservoir, and between the carburetor chamber and atmosphere when the starter is not operating.

It will be further noted that this valve structure exemplifies a construction in which a normally closed inlet valve 60 and a normally open relief valve 67 are provided, and that the relief valve is closed and held closed by the operator upon the opening of the inlet valve, which construction is not necessarily limited in its use to a starting system. By the term "manually operated" I mean either by the foot or hand of the operator.

I desire it to be understood that this invention is not to be limited to any specific form or arrangement of parts except in so far as such limitations are specified in the claims or necessitated by the prior art.

I claim:

1. In engine-starting apparatus using compressed air, the combination with the compressor driven by the engine and a reservoir, of a starter valve controlling the passage of air from the reservoir to the starter mechanism, a valve controlling the passage of air from the compressor to the reservoir, a spring interposed between said valves to normally close the same, and means under the control of the operator for opening the starter valve.

2. In engine-starting apparatus using compressed air, the combination with the compressor driven by the engine and a reservoir, of a starter valve controlling the passage of air from the reservoir to the starter mechanism, a valve controlling the passage of air from the compressor to the reservoir, a spring interposed between said valves to normally close the same, and means, including a push-button, under the control of the operator for opening the starter valve.

3. In engine-starting apparatus using compressed air and a pressure feed carburetor, the combination with the carburetor and the compressed air reservoir, of a casing, an inlet valve in said casing controlling the passage of air from the reservoir to the carburetor, a push-pin for operating said valve cooperating with said casing to form a relief passage and provided with a valve to close said relief passage when opening said inlet valve, and means for moving said pin.

In testimony whereof, I affix my signature.

NIELS A. CHRISTENSEN.
